UNITED STATES PATENT OFFICE.

DOUGLAS P. LEWIS, OF CINCINNATI, OHIO.

ATTACHMENT FOR OPEN FIRE-PLACES.

SPECIFICATION forming part of Letters Patent No. 410,169, dated September 3, 1889.

Application filed August 24, 1888. Serial No. 283,613. (No model.)

To all whom it may concern:

Be it known that I, DOUGLAS P. LEWIS, a citizen of the United States, residing in Cincinnati, in the county of Hamilton and State 5 of Ohio, have invented a new and useful Improvement in Attachments for Open Fire-Places, of which the following is a specification.

This invention relates to the improvement 10 of an attachment to open fire-places which was patented in the United States of America by Douglas P. Lewis, Andrew M. Johnson, and John W. John, dated March 22, 1887, and numbered 359,868; and the principal object 15 of the new improvement is to construct the parts in such a manner as to still give a high degree of economy in the saving of fuel, and at the same time to better adapt the attachment to every variety of fire-places without 20 the outlay of so much extra time and money as has hitherto been necessary in many cases.

Referring to the drawings, Figure 1 is a view of the improved attachment as it appears when separated from the fire-place, 25 with parts broken away to show circulation of the heated gases. Fig. 2 is a back view of the attachment, showing the relative position of the parts. Fig. 3 is a sectional view near one side on the dotted line s, Fig. 2, showing 30 also a section of the brick-work of the chimney and the position in the fire-place the attachment occupies when ready for use. In Fig. 3 is also shown part of the the top of a mantel.

The general construction is the same as the 35 attachment shown in Patent No. 359,868, before referred to, in which the parts A, B, and B' are hollow castings. The part A forms a hollow lintel, which at each end is in communication with the top end of the hollow jambs B and B', and this hollow lintel has an opening at the under side, which extends its whole length from the inside of hollow jamb B to the inside of hollow jamb B'. The jambs B and B' stand upon the hearth, 45 and at the back part of each, close to the hearth, is an opening D and D'. At this point is the principal improvement upon Patent No. 359,868 hereinbefore referred to.

In my improved attachment herein de- 50 scribed the hollow base shown in Patent No. 359,868, hereinbefore referred to, is en-

tirely dispensed with, and in the place of this hollow base is an ash-pit R, which has passages on each side which convey the products of combustion from the jambs B and B' to 55 the rear, as will be hereinafter explained. The hearth forms the bottom of the ash-pit, and the sides and back are composed of plates of cast-iron of about eight inches in width. The back plate has a door I, which can be 60 opened for the purpose of cleaning out the soot which may deposit at the rear of the attachment. The side and back plates, which form the ash-pit, are flanged laterally at the top edge to increase their thickness, and thus 65 form the foundation for the fire-brick lining of the attachment.

It must be understood that in the application of this attachment the width between the jambs and the height between the arch and 70 hearth of a fire-place form an opening which is smaller than the greatest height and width of the attachment, so that when the attachment is applied to a fire-place the hollow 75 jambs B and B', together with the hollow lintel A, have a position in front and entirely outside of the brick-work of the chimney, as shown in Fig. 3, and only the rear projecting parts have a position inside the jambs and arch of the fire-place, as shown in Figs. 2 and 3. The 80 entire opening of the fire-place down to the hearth is thus covered by the attachment. The outside width of the box which forms the ash-pit is always less than the width between the jambs of the fire-place, so that when the 85 attachment is in proper position a space is left at each side of the ash-pit box to form 90 passages which extend directly to the rear and connect the flue at the back of the attachment with the openings D and D' at the lower end of the hollow parts B and B'. The bottom of these side passages is the hearth, and the top is formed by horizontally-projecting plates N and N', one of these plates being plainly shown just above opening D in 95 Fig. 2.

No grate is shown in the attachment; but if one is placed in the usual position above the ash-pit and a fire built the heated air, together with the products of combustion, will 100 rise and be carried by the inward draft at the long opening at the under side of the hollow

lintel A to the right and left, thence downward through the hollow jambs B and B' to the openings D and D', thence directly rearward through the passages at each side of the 5 ash-pit R, and thence into and upward in the flue L. There is a damper placed in the throat of the hollow lintel A, which can be either wholly or partially closed to stop the draft where it is necessary to bank the fire in 10 the grate, or for any other purpose that may arise in practice.

What I desire to secure by Letters Patent, is—

The heat-radiating attachment for open fire-

places described, having openings D and D' 15 at the lower ends and rear side of hollow jambs B and B', which openings are connected directly to the rear with the flue L by means of passages P, formed between the plates that comprise the side walls of the 20 ash-pit R, the jambs of the fire-place, the hearth, and the plates N and N', as hereinbefore described.

DOUGLAS P. LEWIS.
